(57) **CLAIM**

We claim the ornamental design for an electric vehicle battery, as shown and described.

DESCRIPTION

FIG. 1 is a perspective view of an electric vehicle battery; FIG. 2 is a left side view thereof; FIG. 3 is a right side view thereof; FIG. 4 is a front view thereof; FIG. 5 is a rear view thereof; FIG. 6 is a top view thereof; FIG. 7 is a bottom view thereof; and, FIG. 8 is a second perspective view thereof, shown in an environment of use.

The broken lines in the figures depict portions of the article and environmental structure which form no part of the claimed design.
